EASY WALKER APPLIANCE

Laurence Leo Reichenbach, Astoria, N.Y.

Application October 15, 1957, Serial No. 690,343

1 Claim. (Cl. 135—45)

This invention relates to walking devices and, more particularly, to an attachment for canes, crutches, and the like.

It has been found that the substantially rigid conventional types of canes and crutches transmit a substantial amount of impact shocks to the user which is suffering from some particular ailment requiring the use of such appliance. In many cases, such shocks are extremely painful to arthritics, persons having fractured bones, sprained backs, hips, and the like. It is therefore an object of the present invention to provide an attachment for various types of walking appliances that is extremely simple in construction, efficient in operation, and which will absorb many of the shocks ordinarily transmitted to the user so as to reduce the pains and suffering of such handicapped individuals.

It is another object of the present invention to provide an attachment for walking appliances which may be selectively supported upon the appliance in a particular manner to alleviate different types of pains.

Still a further object of the present invention is to provide an attachment for walking appliances that adds to the comfort and rehabilitation of the patient and which can be manufactured in large quantities at relatively low cost so as to be readily available to all afflicted individuals when required.

All of the foregoing and still further objects and advantages of this invention will become apparent from a study of the following specification, taken in connection with the accompanying drawing, wherein:

Figure 1 is a perspective view of a cane embodying an attachment made in accordance with the present invention;

Figure 2 is an exploded front elevational view of the device shown in Figure 1;

Figure 3 is an enlarged side elevational view, with parts broken away, showing the details of construction of the apparatus shown in Figures 1 and 2;

Figure 4 is a view similar to Figure 3 showing the parts in an adjusted position;

Figure 5 is an enlarged fragmentary perspective view showing one of the elements forming a part of the present invention;

Figure 6 is an enlarged longitudinal cross sectional view taken along line 6—6 of Figure 3;

Figure 7 is a transverse cross sectional view taken along line 7—7 of Figure 3;

Figure 8 is an enlarged fragmentary side elevational view, with parts broken away, showing the device in operative use with a substantial amount of pressure exerted thereon;

Figure 9 is a fragmentary side elevational view of a modified form of construction for use with a crutch; and

Figure 10 is a side elevational view of a crutch embodying the appliance attachment shown in Figure 9.

Referring now to the drawing, and more particularly to Figures 1 to 8 thereof, a compressible shank 17 for

2

walking appliances is shown in operative association as an integral part of a cane 12 having a handle 14 and a ground engaging resilient pad 15. This shank 17 comprises a tubular shaft 19 having a fixed sleeve 20 at one end secured thereto by means of a transversely extending pin 22. A slidable sleeve 24 is slidably carried by the opposite end of the shaft 19 and is secured thereto by means of a transversely extending pin 25 which is fixed to diametrically opposite sides of the sleeve 24 and is slidably received within longitudinally extending slots 27 at diametrically opposite sides of the shaft 19. The outer end of the slidable sleeve 24 is provided with a transversely extending wall 29 for forming a seat for one end of a compression spring 32 that is seated at its opposite end upon the transversely extending pin 25. It will thus be recognized that inward movement of the sleeve 24 is resiliently resisted by the compression spring 32. A rigidifying pin 30 extends through the outer end of the sleeve 24.

20 The ground engaging member 15 has a longitudinal bore 40 for receiving one of the aforementioned sleeves 20, 24. The handle 14 includes a reduced shank portion 34 for engaging with the other one of the aforementioned sleeve 20, 24. This reduced shank portion 34 is provided with a longitudinal recess 38 within which a clip plate 35 is secured that has a laterally outwardly extending tongue 36 for frictionally securing the handle 14 in place within the associated sleeve.

25 In actual use, the compressible shank 17 may be used in the position shown in Figure 1 when it is desired to reduce the jar and shock to the back, shoulders, and hips, as well as the arms, to make walking more comfortable for those individuals that are afflicted in those parts of the bodies. However, the shank 17 may be inverted to the position shown in Figure 4 of the drawing for individuals who are afflicted with rheumatism, arthritis, sprains and broken bones in certain parts of the back and hips.

30 With references now to Figures 9 and 10 of the drawing, a compressible shank unit 45 is shown that is particularly suited for use with crutches and the like. This unit includes a tubular shaft 47 having a sleeve 49 fixed to one end by means of a pin 50 and a sliding sleeve 52 adjustably carried by the opposite end. A transversely extending pin 54 extends through and is secured to the end of the tubular shaft 47 received by the sliding sleeve 52. This pin also is slidably received within longitudinally extending slots 55 at diametrically opposite sides of the sliding sleeve 52 to provide for limited reciprocating longitudinal movement. A compression spring 56, seated at one end against the transversely extending pin 54, is seated at the opposite end within the ground engaging tip 58 so as to provide the cushioning action. A crutch 61 provided with a peg 60 of reduced diameter is frictionally secured to the outer end of the fixed sleeve 49 so as to maintain the parts in proper assembled relationship. It will thus be recognized that the crutch is also cushioned in a manner similar to that described in connection with the cane of Figures 1 to 8, so that afflicted persons are afforded the maximum amount of comfort.

35 While this invention has been described with particular reference to the construction shown in the drawing, it is to be understood that such is not to be construed as imparting limitations upon the invention, which is best defined by the claim appended hereto.

Having thus described my invention, I claim as new and desire to secure by Letters Patent:

40 A compressible shank for walking appliances comprising, in combination, a tubular shaft, a fixed sleeve secured to one end of said shaft, a longitudinally slidable sleeve carried by the opposite end of said shaft, means for cushioning the inward movement of said longitudinally

slidable sleeve, means for securing a ground engaging member to one sleeve, and means for securing a body engaging member to the other sleeve, said opposite end of said shaft comprising a pair of longitudinally extending slots at diametrically opposite sides thereof spaced inwardly from the outer extremity of said opposite end of said shaft, a pin extending diametrically through the inner end of said slideable sleeve slidably received within said slots for reciprocating longitudinal movement, a transverse wall within the outer end of said slideable sleeve, and said cushioning means comprising a relatively short stiff compression spring acting between said transverse wall and said pin, wherein said body engaging member comprises a handle having a substantially straight shank of reduced diameter, said shank having 15

a longitudinally extending recess, a clip plate secured to said handle shank within said recess, and a tongue integral with said clip plate extending outwardly therefrom for releasable frictional engagement within said 5 slideable sleeve.
